US00D883015S

(12) **United States Design Patent** (10) **Patent No.:** **US D883,015 S**
Deng et al. (45) **Date of Patent:** **** May 5, 2020**

(54) **FOOD PREPARATION DEVICE AND PARTS THEREOF**

(71) Applicant: **SharkNinja Operating LLC**, Needham, MA (US)

(72) Inventors: **Da Deng**, Newton, MA (US); **Dan Kestenbaum**, Brookline, MA (US)

(73) Assignee: **SHARKNINJA OPERATING LLC**, Needham, MA (US)

(**) Term: **15 Years**

(21) Appl. No.: **29/659,577**

(22) Filed: **Aug. 9, 2018**

(51) LOC (12) Cl. **07-02**

(52) U.S. Cl.

USPC **D7/354; D7/358**

(58) **Field of Classification Search**

(57) **CLAIM**

The ornamental design for an food preparation device and parts thereof, as shown and described.

DESCRIPTION

FIG. 1 is a perspective view of a food preparation device, showing our new design;

FIG. 2 is a front view of the embodiment shown in FIG. 1; FIG. 3 is a rear view of the embodiment shown in FIG. 1; FIG. 4 is a side view of the embodiment shown in FIG. 1; FIG. 5 is another side view of the embodiment shown in FIG. 1;

FIG. 6 is a top view of the embodiment shown in FIG. 1; and,

FIG. 7 is a bottom view of the embodiment shown in FIG. 1.

The broken lines in the figures are for environmental purposes only and form no part of the claimed design.

1 Claim, 7 Drawing Sheets
